UNITED STATES PATENT OFFICE.

NIELS O. STARKS, OF MADISON, WISCONSIN, ASSIGNOR TO THE FULLER & JOHNSON MANUFACTURING COMPANY, OF SAME PLACE.

WHEELED PLOW.

SPECIFICATION forming part of Letters Patent No. 616,984, dated January 3, 1899.

Application filed January 31, 1898. Serial No. 668,661. (No model.)

To all whom it may concern:

Be it known that I, NIELS O. STARKS, a citizen of the United States, residing at Madison, in the county of Dane and State of Wisconsin, have invented certain new and useful Improvements in Wheeled Plows, of which the following is a specification.

My present invention pertains to improvements in wheeled plows, the advantages and construction of which will be hereinafter set forth, reference being had to the annexed drawings, wherein—

Figure 1 is a top plan view of the machine; Fig. 2, a side elevation; Figs. 3 and 4, side elevations of certain portions of the machine, the main land-wheel being omitted or shown only in dotted lines; Fig. 5, a perspective view of certain details of construction, and Fig. 6 a side elevation showing the relation of certain parts under varying conditions.

One object of the present invention is to provide means for raising and lowering the plow and to so construct said parts or means that the plow may be elevated when it strikes an obstruction.

A further object is to provide suitable means for guiding the front furrow-wheel, whereby the machine may be manipulated and turned with facility.

A still further object is to provide suitable spring mechanism for forcing or drawing the plow into the ground.

Other advantages are present and will present themselves in the following description and claims.

The main frame of the machine consists, essentially, of the bars 1 and 2, bent to form, as shown in Fig. 1, and connected at their rear ends to a casting 3, which is so shaped as to form an upright bearing for the vertical stem 4 of the rear axle 5, upon which is mounted the rear furrow-wheel 6. The forward ends of said bars 1 and 2 are directly attached to casting 7, which, as in the case of casting 3, is formed with a vertically-disposed opening or bearing in which is mounted a cranked arm 8, said arm having secured to its lower end a short stud-axle for the front furrow-wheel 9. The bearing 10 for axle 11 of the land-wheel 12 is mounted between two

bars 13 and 14, both being bolted to the main bar 1 and the latter, 14, extended forward and connected to the block or head 15. In this head there is journaled a post 16, having secured to its upper end an arm 17, extending to both sides of its center. Upon that end of the arm 17 next to the furrow-wheel 9 there is mounted an adjustable seat 18, to which is attached the pole 19, while the opposite end of the arm is pivotally connected by a bar 20 with the cranked arm 8, as clearly indicated in Figs. 1 and 2. Through these connections it will be seen that as the pole is turned the front furrow-wheel will also be turned to a similar degree. By thus constructing the parts the pivot-point of the pole and point of attachment of the evener or trees to the plow-beam are approximately in alinement.

It is manifest that a wheel and chain connection or gearing may be employed instead of the construction just set forth.

The usual or any approved form of device may be employed for raising or lowering the forward portion of the frame upon the vertical member of the cranked arm 8—such, for instance, as the lever 21 and link 22. Similar devices are employed in connection with the land-wheel 12, so it will be seen that the frame may be raised or lowered, as desired.

The beam 23 carries at its forward end a clevis 24 and has attached to its lower rear end the plow 25. The beam has secured to it two brackets or castings 26 and 27, in the first of which is journaled a bail 28, said bail being formed as an integral part of or rigidly affixed to the axle 11. As shown in Fig. 1, the bail is journaled in brackets secured to the side bars 1 and 2. A bail 29 is journaled in the bracket or casting 27, the ends of the bail being seated in bearings formed in depending brackets 30 and 31, secured to the bars 1 and 2.

A link or eye 32, Figs. 3 and 4, is pivotally secured to the forward part of the frame and passes around the beam, a pin 33, passing through the beam, determining their relative position when the beam is lowered, as in Fig. 4.

At the rear end of the frame there is provided a bearing 34, in which is mounted a

shaft 35, Fig. 5, said shaft having formed or secured upon one end an arm 36, while the opposite end is provided with a squared portion 37 and a threaded end. A lever 38 is 5 loosely mounted upon the projecting end of the shaft 35, while secured upon the squared portion 37 is a block 39, provided with a recess 40, formed by the long lip 41 and the relatively short lip 42. The lever 38 carries 10 a spring-actuated pawl or detent 43, designed under certain conditions to enter the recess 40 of the block, and thus lock the lever and shaft 35 together. Arm 36 is pivoted to a link 44, which in turn is pivotally connected 15 to the rear of the bracket 27 or directly to the plow-beam, as may be desired. Said link 44 extends up past its pivotal connection with the arm 36 and has secured in a lateral projection 36°, at its upper end, an eye 45. A 20 set-screw 46 is also mounted in the upper portion of the extension of the link 44, the screw serving to adjust the relation of the parts, as will presently appear.

Secured to the plow-beam is an arm 47, and 25 between the rear end of said arm and eye 45 there is secured a coiled spring 48. Pivoted upon the bracket or bearing 27 is a latch 49, provided with a nose 50, the latch extending into link 44, Figs. 1 and 2, and coming in contact with the upper beveled end of arm 36. 30

A suitable seat 51 and foot-rests 52, 53, and 54 are provided, the rest 54 being attached directly to the beam, as shown. A heavy coiled spring 55 extends forwardly from the 35 lower rear portion of the frame and is connected to the rest 54.

To maintain the rear wheel in place, an arm 56 is secured upon the upper end of stem or post 4, a spring-latch 57 engaging with the 40 end of the arm, the latch in turn being controlled by rod 58 and foot-lever 59.

With the parts in the position indicated in Figs. 1, 2, and 3 the plow is elevated and the beam occupies its highest position as well as 45 being drawn back as far as possible. If it now be desired to lower the plow, the operator draws the lever 38 forward, the pivoted pawl 43 being in engagement with block 39, and consequently rotating shaft 35 and with 50 it carrying arm 36 forward and downward, the latch 49 meanwhile having been elevated, so as to permit its nose 50 to ride over the upper end of arm 36. As the arm 36 moves forward and downward it will cause the link 55 44 also to move forward and downward, the parts moving from the position indicated in Fig. 3 to that shown in Fig. 4. Arm 36 and link 44 form a toggle which serves to force the beam forward and downward, the bails 60 28 and 29 permitting the beam to be lowered and moved bodily forward. Spring 48 also tends to draw the toggle into its straightened position and in so doing serves to force the plow into the soil and to hold it there. When 65 the parts are in the position shown in Fig. 4, the end of screw 46 bears upon arm 36 and

serves to prevent the pivotal points of the toggles from coming into exact alinement. Spring 55 is put under tension as the beam is moved forward and downward, and when 70 the beam is lowered to its greatest extent said spring also serves to hold it in this position. As the lever 38 comes to its forward position the tail of latch 43 comes into contact with a projecting arm 60, Figs. 1, 3, and 75 6, and the nose of the latch is withdrawn from the recess 40. The position which the parts occupy is indicated in full lines in Fig. 6. If, however, the operator should raise the lever, the latch would immediately engage with the 80 block, locking the parts together, whereupon upon a further rearward movement of the lever the beam and plow would be elevated.

It will be noted, as above pointed out, that when the plow is lowered into its working position lever 38 is wholly disconnected from the working parts, and should the plow strike an obstruction it would rise up, breaking the line of the toggle, but leaving the lever 38 down, the relation of the parts being shown 90 in the full and dotted lines of Fig. 6. From the relation of the springs, as shown, spring 55 serves when the plow is down to hold it down; but when the plow encounters an obstruction and is raised to a certain extent the 95 spring then acts to elevate it to its highest degree. If after having struck an obstruction and the plow is elevated the operator desires to lower the plow, all that is necessary is to bring the lever back until the latch engages the block, when the parts will be locked together ready for another forward movement.

The arrangement of the parts whereby the plow may be automatically raised without 105 having the lever fly back past the operator is of marked advantage for obvious reasons.

Inasmuch as the beam is supported by bails which are journaled in the frame, the plow must of necessity always occupy a horizontal 110 position.

By adjusting the screw 46 the toggle-joint may be regulated, and by tightening the spring the plow will be drawn more firmly into the ground. By loosening the spring the 115 plow will more readily jump up when it strikes an obstruction, and by so doing will relieve the whole structure, as well as the team, from what might possibly be a severe 120 shock in bringing up solidly.

It is manifest that other arrangements and locations of springs will suggest themselves for drawing the plow into the ground, while at the same time permitting it to rise freely when encountering an obstruction. So, too, 125 either of the springs may be omitted and the operation of the parts will be the same; but of course the single spring would have to do the work of both and would not work so advantageously.

Instead of journaling the bails in the brackets, as shown, it is manifest that they could 130

be journaled directly in the frame, and the claims are to be read in light of this statement.

Having thus described my invention, what I claim is—

1. In a wheeled plow, the combination of a frame; a cranked arm 8 journaled in the frame; a wheel carried at the lower end of the arm; arm 17 pivotally supported in the forward part of the frame; a link or rod 20 connecting one end of said arm with the outer end of the cranked arm 8; and a pole connection mounted upon the opposite end of the arm 17.
2. In a wheeled plow, the combination of a frame; a cranked arm 8 journaled in the frame; a wheel carried at the lower end of the arm; an upright post 16 rotatably mounted in a bearing 15 secured at the forward end of the frame; an arm 17 secured in the head of said post; a link or rod 20 connecting one end of arm 17 with the outer end of cranked arm 8; and a pole connection carried upon the opposite end of the arm 17.
3. In a wheeled plow, the combination of a frame; a plow-beam carried by bails journaled in said frame; a toggle connection between said frame and the beam; a spring serving to force the beam down; and means for moving the toggle.
4. In a wheeled plow, the combination of a frame; a plow-beam hung in said frame; a toggle connection between the beam and the frame; and a spring serving to force the beam down.
5. In a wheeled plow, the combination of a frame; a plow-beam connected thereto by bails pivoted in the frame; a toggle connecting said beam with the frame; means for moving said toggle; and a spring connected to the toggle and the beam serving to force the beam toward its lowermost position.
6. In a wheeled plow, the combination of a frame; a plow-beam carried by bails pivoted in the frame; a toggle-joint connecting said beam and the frame; a lever for moving said toggle; and connections between said lever and the toggle, substantially as described, whereby as the toggle is straightened and the beam lowered, the connecting means are thrown out of operation.
7. In a wheeled plow, the combination of a frame; a plow-beam carried thereby and capable of being raised and lowered; means for raising and lowering said beam; a lever for operating said means; and a connection between said lever and said means designed when the beam is lowered to be thrown out of operative relation.
8. In a wheeled plow, the combination of a frame; a plow-beam carried by bails journaled in said frame; a toggle-joint between said frame and the beam; a lever for operating said toggle; and connecting devices between said lever and the toggle designed when the toggle is straightened and the beam lowered to be thrown out of operative relation, where-

by the beam may be raised when the plow strikes an obstruction, without raising the lever.

9. In a wheeled plow, the combination of a frame; a plow-beam carried by bails journaled in said frame; a toggle connection between said frame and the beam; a lever for operating said toggle; connecting devices between said lever and the toggle designed when the toggle is straightened and the beam lowered to be thrown out of operative relation; and a spring for forcing the beam downward.

10. In a wheeled plow, the combination of a frame; a plow-beam carried by bails journaled in said frame; a toggle connection between said frame and the beam; a lever for operating said toggle; connecting devices between said lever and the toggle; and a spring connected to the toggle and the beam serving as the beam is lowered and the toggle straightened, to force said beam downward.

11. In a wheeled plow, the combination of a frame; a plow-beam carried by bails journaled in said frame; an arm 44 connected to the beam; an arm 36 pivoted to the arm 44 and likewise connected to the frame; means for moving said arm 36; and a latch 49 carried by the beam designed when said beam is elevated to come into contact with the upper end of the arm 36 and to thereby lock the beam in its elevated position.

12. In a wheeled plow, the combination of a frame; a plow-beam carried by bails journaled in said frame; arm 44 connected to the beam; an arm 36 pivoted to said arm 44 and likewise connected to the frame; a latch 49 carried by the beam and designed when said beam is elevated to come into operative relation with the arm 36; a spring connecting the upper extended end of the arm 44 to the beam; and means for moving said arm 36, substantially as described.

13. In a wheeled plow, the combination of a frame; a plow-beam carried by bails journaled in said frame; an arm 44 pivoted to the beam; an arm 36 pivoted to said arm 44 and likewise connected to the frame; a spring mounted between the beam and the upper extended end of the arm 44; and a lever connected to the arm 36.

14. In a wheeled plow, the combination of a frame; a beam carried by bails journaled in said frame; a toggle connection between said beam and frame; a lever for operating said toggle; and connections between said lever and the toggle designed as the beam is lowered and the toggle straightened to be thrown out of operative relation therewith, substantially as described.

15. In a wheeled plow, the combination of a frame; a beam mounted upon bails journaled in said frame; a toggle connection between said beam and the frame for forcing said beam downward; a lever for operating said toggle, detachably connected thereto; and means for releasing the lever as the beam is lowered.

16. In a wheeled plow, the combination of a frame; a beam mounted upon bails journaled in said frame; a toggle connection between said beam and the frame; a shaft 35 connected to one member of said toggle and journaled upon the frame; a lever loosely mounted upon said shaft; a block carried upon the end of said shaft; a pivoted latch carried by the lever and designed to engage the block; and an arm secured to the frame for releasing the pivoted latch from the block when the lever is thrown forward and the toggle straightened.

17. In a wheeled plow, the combination of a frame; a beam carried by bails journaled in said frame; a toggle connection between said beam and the frame; a shaft 35 connected to one member of the toggle and journaled upon the frame; a lever loosely mounted upon said shaft; a block 40 secured upon the end of the shaft provided with the short lip 42 and the relatively long lip 41; a pivoted latch carried by the lever designed under normal conditions to engage the block; and 25 an arm 60 secured to the frame in line with

the lever for releasing the latch from the block as the lever is thrown forward and the toggle straightened.

18. In a wheeled plow, the combination of a frame; bails 28 and 29 journaled in said frame; a plow-beam carried by said bails; means for raising and lowering said beam; and an extension-axle 11 forming a part of the bail 28, substantially as and for the purpose described.

19. In a wheeled plow, the combination of a suitable frame; a beam carried by bails journaled in said frame; toggle mechanism for raising and lowering said beam; a spring 48 connected with the toggle and the beam; 40 and a spring 55 extending from the rear part of the frame forwardly and connected to the beam, substantially as and for the purpose described.

In witness whereof I hereunto set my hand 45 in the presence of two witnesses.

NIELS O. STARKS.
